3 SHEETS-SHEET 3.

UNITED STATES PATENT OFFICE.

GEORGE P. FINNIGAN, OF WILTON-ON-JAMES, NEAR RICHMOND, VIRGINIA.

SYSTEM OF TRAIN CONTROL.

1,302,345.

Specification of Letters Patent. Patented Apr. 29, 1919.

Application filed July 10, 1914. Serial No. 850,075.

To all whom it may concern:

Be it known that I, GEORGE P. FINNIGAN, a citizen of the United States, residing at Wilton-on-James, near Richmond, Henrico county, State of Virginia, have invented certain new and useful Improvements in Systems of Train Control, of which the following is a specification.

My invention relates to a system of and apparatus for controlling the speed of or giving indications or signals upon a moving vehicle of any character, but more commonly an electric or steam railway car or train; and my invention resides more particularly in such system or apparatus which shall produce different controls or give different indications or signals in response to different or varying speeds of the vehicle, car or train; or which shall produce tapering or varying controls or indications on the car or train as it proceeds, so that traffic may be expedited by employing cars or trains following each other at very short intervals. To these ends I employ permanent magnets or electro-magnets, or simple unmagnetized members of magnetizable material, or combinations of them disposed in the vehicle's path in such manner as to influence a circuit or circuits on the vehicle by inductive effects resulting from changes of magnetic flux threading a winding or circuit carried by the vehicle.

And my invention resides also in such a system where controls, indications or signals are effected both upon the moving vehicle and upon instrumentalities located along its path of travel, the effect produced by the devices along its path of travel being mutual, or being solely upon a device upon the vehicle or solely upon a stationary device, as on a permanent way.

And my invention resides also in a system wherein controls, indications or signals are effected by instrumentalities along the permanent way in response to vehicle or train movement without any circuit or special device upon the vehicle or train, other than some magnetizable material which may change the flux of a permanent or electro-magnet disposed in the path of travel, such magnetizable material generally being the car wheel or wheels, or the car wheels and axles.

For an illustration of several of the many

forms my invention may take reference is to 55 be had to the accompanying drawings, in which:

Figure 1 is a diagrammatic view of apparatus and circuits for producing a control or indication or signal upon a moving vehicle or train upon movement of the same past magnetic flux producing means whose flux is made different at different times in response to the condition of some track circuit or any other circuit. 65

Fig. 2 is a diagrammatic view of apparatus and circuits whereby there is selective or varying response to varying vehicle or train speeds by means on a car or train influenced by means producing magnetic flux 70 or a magnetizable member upon the permanent way.

Fig. 3 is a diagram of apparatus and circuits for effecting controls, indications or signals, which may be selective in response 75 to varying vehicle speeds, the stationary apparatus along the permanent way comprising magnetic means disposed near a contact conductor from which power is delivered to the car or train. 80

Fig. 4 is a diagram of circuits and a simplified perspective view of a selective translating device.

Fig. 5 is a diagram of apparatus and circuits involving an electro-magnet disposed 85 along the path of travel of the car or train for producing mutual effects upon the devices on car or moving vehicle and devices upon the trackway, or upon either alone.

Fig. 6 is a diagrammatic view of apparatus and circuits whereby, with the employment of permanent magnets of different flux values along the path of travel, track circuits are employed for producing indications or controls upon the car or train or by 95 devices along the trackway.

Fig. 7 is a diagrammatic view of apparatus and circuits resembling those of Fig. 6 but employing an electro-magnet along the path of travel of the car or train. 100

Fig. 8 is a diagrammatic view of apparatus or circuits, involving track circuits, for procuring variable or tapering controls or indications or signals upon the moving car or train. 105

Fig. 9 is a diagrammatic view of apparatus and circuits whereby effects are produced upon control, indicating or signal de-

vices disposed along the trackway, without recourse to circuits or devices upon the car or train.

Fig. 10 illustrates a modified form of permanent magnet or magnetizable member.

Fig. 11 illustrates a different method of application of the permanent magnet or magnetizable member.

Referring to Fig. 1, T, T represent sections of rails of iron, steel, or other magnetizable material upon which travel the wheels W, W and axle A, also of iron or steel or of other magnetizable material. Carried by the car or train of which the wheels and axle are a part are the wheel coils C, C loosely surrounding the wheels and disposed parallel to the rails between the axle and the rails. Or an axle coil like C₁ of Fig. 2 may be used instead of or cumulatively with wheel coils C, C. These coils, when more than one is used, are so wound or so connected that the electro-motive forces produced therein are cumulative, the coils C, C being connected in circuit with the battery or other source of current B and the translating device t, which may be of any suitable or desired type for giving or controlling various indications or controlling the speed of the vehicle as by controlling the air or other brakes or controlling the engine or motor; it is here assumed, by way of example only, as of the character shown in Fig. 4. In this circuit may be inserted an adjustable resistance R₁, all or more or less of which may be cut out.

Disposed in the ballast or trackway is a permanent magnet P, in the form of a bar or plurality of bars or plates whose one magnetic pole is beneath or near one rail T while its other magnetic pole is near or beneath the other rail T. Between the poles of the permanent magnet P and the rails T, T are disposed magnetizable cores c, c preferably of soft iron or of other similar magnetizable material, connections of low magnetic reluctance b being made between the cores c, c and the rails T, T; and between these cores and the poles of the permanent magnet P a low magnetic reluctance 50 connection is provided. If the rails T, T are used in a track circuit insulation I may intervene to prevent a short circuit between the rails T, T through the permanent magnet P. Surrounding the cores c, c are the 55 electro-magnet windings w, w so wound or connected as to be cumulative in their effect, these windings w, w being connected in circuit with the battery or other source of current B₁ and the variable resistance R more or less of which is short circuited by the movable contact a mechanically connected to the core c₁ of a solenoid s or any other electro-magnetic device or translating device, the terminals of the winding of the 65 solenoid s being shown as connected to the

conductors 1 and 2 of a track circuit (as shown for example in Figs. 6 and 7) or any other signal or control circuit. The upward movement of the contact a is opposed by a spring s₁₂.

As the wheels and axle move over the rails T, T past permanent magnet P the reluctance of the magnetic circuit of the permanent magnet P is for a time reduced accompanied by magnetic flux in the coils C, C, producing an electro-motive force superimposing a current upon the current produced in the car circuit by the battery B with the result that the magnetism of the translating device t will at some moment be 80 changed to a degree to effect a control or an indication or signal.

The direction of the current through the windings w, w from battery B₁ is such that they produce magneto-motive force opposing the magneto-motive force of the permanent magnet P so that when these windings w, w are energized, they produce with the permanent magnet P a flux through coils C, C which is less than that produced by the permanent magnet P when these windings are not energized. In consequence the amount of flux passing through the wheel coils C, C will depend upon the current strength in the circuit of the windings w, w and this is varied by the adjustment of the amount of resistance R in the circuit of the battery B₁. And this in turn is accomplished by the solenoid s which when strongly energized will raise the contact a 100 and cut resistance out of circuit and when the current through the winding of the solenoid s is diminished the spring s₁₂ will move the contact a downwardly to such point that the force exerted by the spring is balanced by the attractive force of the coil s and since now more resistance is in the circuit of the battery B₁ the flux through the wheel coils C, C will be greater. It will accordingly be seen that in response to different current strengths in the solenoid s different amounts of flux will pass through the wheel coils C, C with resultant different effects upon translating device t in the circuit of the battery B. In consequence the response of the translating device t will depend upon the condition of the circuit including the conductors 1 and 2. These conductors 1 and 2 may be in circuit with a source of current, as in a track circuit (as shown for example in Figs. 6 and 7) or any other circuit controlled in any desired way.

It will be understood that the device t will respond in varying degrees to varying car speed even when the member P and the associated track devices described are omitted and a simple magnetizable bar of soft iron or steel or the like extends across the trackway, for in such case the magnetic reluctance of the magnetic circuit on the car compris-

ing wheels W, W and axle A will change as the car passes the bar with resultant current fluctuations of different intensities for different car speeds in the car circuit.

5 In Fig. 2 there is associated with the rails T, T the preferably laminated bar or mass M of soft iron or steel or similar magnetizable material, such as Russian iron, it being understood the bar M may be magnetized 70 permanently as by coil traversed by current. Between the ends of the bar M and the rails T, T may be disposed soft iron or soft steel or similar cores c, c, insulation I being provided if necessary. Surrounding these 10 cores c, c, are the coils or windings w, w connected cumulatively with each other in a circuit including the battery or other source of current B₂, adjustable resistance R₂ and the winding w₁ of a translating device t₁ of any 15 suitable type, but here illustrated as comprising a permanent magnet p having a soft iron or steel or similar pole c₁ surrounded by the winding w₁. Cooperating with the pole c₁ are reed or other armatures or 20 tongues a₁ and a₂, which may themselves be permanently magnetized, or may be in any other suitable magnetic or magnetizable condition. The armatures a₁ and a₂ are normally retracted, as by their own spring 25 effects, against the back stops s₁ and are adapted to engage respectively, when attracted with sufficient force, the contacts c₂ and c₃ connected respectively with one terminal of the solenoid windings s₂ and s₃ 30 whose other terminals are connected together and with one terminal of battery or other source of current B₃ whose other terminal connects with both of the armature members a₁ and a₂. The solenoid core c₄ is 35 common to the coils s₂ and s₃ and carries at its lower end a valve v having a port p₁, the valve v in its closed position, illustrated, closes connection between the passages p₂ and p₃ in which is adapted to move a motive 40 fluid, such as steam, compressed air, or any other medium under pressure which may be employed to effect any control, or indication or signal. Or the solenoid c₄ may be employed to adjust or vary the resistance in an 45 electric circuit or to effect any other adjustment or change for purposes of varying control, indication or signal by devices along the trackway.

Around the axle A of the car may be disposed a coil or winding C₁ (or wheel coils as in Fig. 1 may be used instead of or cumulatively with coil C₁) connected in circuit with an adjustable resistance R₁, all of which or more or less of which may be cut out of or 50 into the circuit which includes besides a source of direct current or battery B₄ and a source of alternating current A₁ controlled respectively by switches s₄ and s₅. This circuit may also include if desired a translating device t of any suitable or desired type, 55

and may be, for example, a translating device similar to t₁ or of the character illustrated in Fig. 4.

When the switch s₄ is closed, and the switch s₅ is open, the source B₄ only will be 70 in circuit on the car. A direct current, whose strength may be adjusted by resistance R₁, will flow through the coil C₁, magnetizing the axle A and the wheels W, W, the wheels being of opposite polarities. 75

In such case, a car passing over the bar M causes a change in the magnetic flux through the coils w, w which change is effected or controlled or modified by the magnetic flux produced by the coil C₁. This change in 80 magnetic flux through the coils w, w causes the production of a current by induction, in the circuit of these coils thus changing the attractive force normally exerted by the core c₁ upon the reeds or armatures a₁, a₂. For a 85 given speed of car or train this change in attraction will be of predetermined amount and may be assumed to be sufficient to attract armature a₁ which may be moved so close to or into contact with the pole c₁ as to be retained in attracted position and thereby close and hold closed the circuit from battery B₃ and armature a₁, contact c₂ and solenoid winding s₂, it being assumed that the current impulse was not sufficient to attract 90 the armature a₂. The winding s₂ now being energized will attract the core c₄ upwardly a certain distance in opposition to spring s₆ thereby opening the valve somewhat and allowing the passage of motive fluid in passage p₂ and p₃ to effect any desired result. 100

If however the train should pass over the bar M at higher speed than above assumed the current impulse in the circuit of the winding w₁ will be greater than before and 105 sufficient to attract both armatures a₁ and a₂ and hold them in their circuit closing positions; or if the armature a₁ had previously been attracted and held in circuit closing position a succeeding train might pass at 110 such higher speed as to cause the subsequent attraction and holding of armature a₂ to close the second circuit. In either case, both circuits are closed and therefore both windings s₂ and s₃ are energized with resultant 115 stronger pull upon core c₄ which will rise to a greater distance in opposition to spring s₆ and open the valve v still farther to cause a greater degree of control or indication or response of any kind to the greater flow of 120 motive fluid or medium through passages p₂ and p₃.

It is thus seen that any device of any type disposed along the trackway may be controlled or operated to different degrees corresponding with different degrees of train speed. 125

In case the switch s₄ is open and s₅ is closed, alternating current will pass through the axle coil C₁. 130

And it will be further understood that in any of the above cases the source B_2 may be omitted, but in such case there is likely to be less delicacy and certainty of action, as later 5 explained in connection with Fig. 4. When the translating device t is employed in the arrangement of Fig. 2, it also will respond upon passage of the car over bar M and produce any suitable control, indication or 10 signal upon the train or car. And it will respond when the bar M is magnetized, either permanently or by a winding traversed by current, and also in the case where the bar M is simply a mass of soft iron or 15 steel or like material.

In Fig. 3 there is shown an arrangement whereby results similar to those described in connection with Figs. 1 and 2 may be procured in connection with an electric rail- 20 way receiving its motive power from a trolley wire, third rail or other contact conductor.

The contact conductor illustrated in this case is a trolley or overhead conductor c_5 carried by the insulator I_1 supported by the usual span wire w_2 . In definite relation with the conductor c_5 is secured the permanent magnet P_1 which may be suitably insulated from the conductor c_5 . The permanent magnet may have the soft iron or soft 25 steel or similar pole cores c_6 surrounded by windings w_3 adapted to be connected in circuit with either a direct current source B_3 or alternating current generator A_2 , brought 30 into circuit respectively by the switches s_7 and s_8 . In the circuit may be a translating device t of any suitable character, for example, such as above described.

Carried by the moving vehicle is the trav- 40 eling contact or trolley wheel w_{13} contacting with the conductor c_5 in the well-known manner. The wheel w_{13} may be carried by a trolley pole or other member p_4 which carries also the core c_7 adapted to pass be- 45 tween the cores c_6 , c_8 as the electric car or train passes the permanent magnet P_1 . On the core c_7 is the winding w_4 connected in circuit with a source of current as a battery B_6 and a translating device t of any suitable 50 type, such, for example, as above described.

In this case the operation is similar to those described in connection with Figs. 1 and 2.

Where the control or indication to be effected is that of some device along the track- 55 way, the winding w_4 and its circuit on the car may be omitted, and then, when the core c_7 is either a permanent magnet or soft iron or soft steel, indications or controls will 60 nevertheless be effected by the device t in any circuit with the windings w_3 . And in such case also the magnet P_1 need not be a permanent magnet but may be of soft iron or soft steel. But when indications or controls 65 are to be effected only upon the car, the

coils w_3 and their circuit may be omitted and the permanent magnet P_1 will effect indications on the car. Or the parts may remain as shown and described and the translating device t in the circuit of the windings w_3 may be omitted. Or the magnet P_1 may be of soft iron or steel either with or without the associated circuit including coils w_3 in which case indications or controls will be produced on the car both when c_7 70 is a permanent magnet or also when it is soft iron or soft steel, it being understood that any arrangement may be used which will change the magnetic flux through a circuit either upon the car, or stationary 75 along the trackway, or both.

In Fig. 4 is shown an arrangement which may be used either upon the car or train or disposed permanently along the track- 80 way. The translating device t_2 is similar to the translating device t_1 described in connection with Fig. 2 except that there is an extra reed or armature here shown. Here are shown three permanent magnets p_5 , p_6 and p_7 separated from each other by air gaps 85 or non-magnetic members m of brass or other suitable non-magnetic metal or other material. Each of the reeds or armatures a_5 , a_6 and a_7 has its one end secured to or dis- 90 posed close to one pole of its coöperating permanent magnet. The free ends of the 95 reeds or armatures are disposed at different distances from the pole cores c_8 , c_9 and c_{10} surrounded by the coils or windings w_5 , w_6 and w_7 , respectively, these windings being 100 shown connected in series with each other and with the battery or other source of current B_7 , adjustable resistance R_1 and the windings w_8 , w_9 which may be either wheel coils like C, C, Figs. 1, 6, 8, 10 and 11, or an 105 axle coil like C₁, Figs. 2, 5 and 7, on a moving car or train, or which may be stationary coils located along the trackway, like coils w , w , Figs. 1, 2 and 9 or C₂, Fig. 5. In any event they are cumulatively connected and 110 are the coils within which occur the magnetic flux changes due to car or train movements. The reeds or armatures, which may 115 themselves be springy or resilient, or which may be supplied with springs, are normally against their back stops s_1 but when fully at- 120 tracted come into and are held by the permanent magnetism in engagement with the contacts c_{11} , c_{12} , and c_{13} respectively, controlling the circuits of solenoids s_9 , s_{10} and s_{11} , a 120 battery or other source of current B_8 being included in circuit.

Common to these solenoid windings is the core c_4 carrying valve v having port p_1 , the valve controlling passages p_3 and p_4 as de- 125 scribed in connection with Fig. 2.

The pole windings w_5 , w_6 and w_7 are traversed by current from the source B_7 , the the strength of current being adjustable by resistance R_1 and of such direction as to 130

oppose the permanent magnets with which they are associated, thus normally preventing the permanent magnets from attracting their respective reeds or armatures. However an impulse comprising both positive and negative half waves being generated in or by the coils w_8 such current also traverses the pole windings but the connections may be such that the first half wave is in the same direction with or assists the source B_7 while the second half opposes it, overcoming it more or less completely, thus allowing the permanent magnet p_5 , for example, to attract and hold its reed or armature a_5 which may be itself permanently polarized only by the effect of the associated permanent magnet p_5 . There being greater air gaps between the other reeds and armatures and their associated poles it will take progressively stronger impulses to cause their attraction to circuit closing position from which it will be understood that with impulses from coils w_5 , w_6 of progressively increasing strength the different reeds or armatures, will be attracted and held in attracted position, thus producing a device which is selectively responsive to varying speeds of trains or cars. As described in connection with Fig. 2, with more and more of the solenoid windings energized the valve v will be lifted to greater and greater distances in opposition to spring s_6 allowing greater and greater amounts of motive fluid to pass through passages p_2 and p_3 to effect varying controls, as of air brakes, or indications or signals depending upon the speed of the car or train.

It will be understood also that the air gaps between the reeds or armatures or poles may be made of the same lengths but the windings w_5 , w_6 and w_7 may have progressively less turns so that it will nevertheless require progressively stronger impulses to attract the successive reeds or armatures. It will be understood also that with different air gaps as illustrated, a single winding may embrace or inclose all the poles.

While I prefer using a source of current such as B_7 the same may be omitted, in which case the connections may be such that the first half of an impulse from the coils w_5 , w_6 will oppose the permanent magnet and release any reed or armature that has been held by it, and the last half will assist the permanent magnet to produce attraction of the reeds or armatures. In such case there is normally no current through the windings w_5 , w_6 and w_7 with the result that the air gaps between the reeds or armatures and their poles must be more carefully adjusted and there will not be the same certainty of action as in the case where the source B_7 is present. And further with the source B_7 present any break in its circuit will result

in the attraction of one or more of the armatures so that such failure is in the direction of giving a control or indication or signal on the side of safety.

In Fig. 5 there is shown what may be considered a reversal of the arrangement shown in Fig. 2. Here the translating device t_1 , battery or source B_2 and adjustable resistance R_2 may be disposed upon the car in circuit with the axle coil C_1 while any suitable translating device t is connected in circuit with the winding or coil C_2 and with either the source B_4 or alternator A_1 and adjustable resistance R_1 permanently disposed along the trackway. In this case the coil C_2 is wound upon the member M which may be permanently magnetized or which may be of soft iron or soft steel. Or the circuit including the translating device t permanently along the trackway may be entirely omitted and the member M may be either permanently magnetized, or magnetized by a solenoid and source of current, or may be simply a bar of soft iron or steel, in any of which cases the translation device t_1 on the car will make responses corresponding to those described in connection with Figs. 1 and 2 and such translating device through its reeds or armature members may effect any control, indication or signal upon the train.

In Fig. 6 the track rails T , T have inserted at suitable intervals, to constitute blocks, the insulation I_2 so that the rails may be made parts of track circuits to the end that the wheels and axles of a car or train may cause short circuit between the rails to effect certain controls or results. Here four blocks are shown, D, E, F, and G, only the right end of block D being shown and only the left end of block G being shown. The direction of travel of cars or trains is that indicated by the arrow. Thus at or near the end of the block D and before the beginning of block E there is disposed across the rails, similarly to the arrangement above described, a permanent magnet P , which is prevented from short-circuiting the rails by insulation I . This magnet has the pole coils c , c connected in circuit with a battery or source of current B_1 , whose one terminal is connected to the end of one rail T of block D, the other terminal connecting through the windings c , c with the contact a_8 which maintains contact with the contact a_9 actuated by the core c_{14} of the solenoid s , and the contact a_9 is adapted to bring into circuit different amounts of resistance R , or to cut the same entirely out of circuit, by engaging the contacts a_{10} , a_{11} and a_{12} , the track circuit including also the coil or winding w_8 , whose other terminal connects to the other track rail T of the block D. The other blocks are similarly equipped and the track circuit of each of the blocks includes at the entrance to each block the sole-

noid s the terminals of whose windings are connected by conductors 1 and 2 to the two rails of the track circuit. By way of example I have here illustrated a car circuit comprising source of energy B and any suitable translating device t associated with a coil C suitably disposed with respect to the wheels W and the axle A, but it will be understood that any of the arrangements herein described may be employed, particularly one which cooperates with a translating device which will give varying degrees of response for giving varying controls, indications or signals, with different train speeds.

15 As the car or train is about to leave a block, its translating device, due to the effect of the permanent magnet, responds to give a control or indication or signal which it will be seen will depend upon the condition of the 20 block or blocks in advance.

With a car in the block G, as indicated, the two rails T, T of that block are short circuited through the wheels and axle with the result that the solenoid s at the entrance 25 to block G is robbed of current and the spring s_{12} has moved the contact a_9 on to the lowest contact a_{12} . This cuts all of the resistance R into track circuit of block F thus 30 weakening the current in the winding w_9 to such degree that the signal Sg moves by gravity or otherwise into danger position, thus indicating that the block G is occupied.

It will be understood that the windings w_9 35 are those of relays or any other devices for controlling positions of signals in well-known manner. The current through the coils c, c at the poles of permanent magnet P at the right end of block F has also been 40 weakened, and, it being remembered that these windings produce magneto-motive-force in opposition to that of the permanent magnet P, their opposing magneto-motive force will now be least with the result that 45 a following car passing over this permanent magnet P at the right end of block F will have produced in its car circuit a very strong impulse which, as hereinbefore described, will produce a selective indication or control 50 depending upon the strength of such impulse. Such impulse may produce an audible or visual signal or may cause the wide opening of the valve v , as by an arrangement such as shown in Fig. 5, taken in connection 55 with Fig. 4, as to powerfully set the air brakes on the train, either to bring the same to rest or to greatly retard the same, assuming that the driver did not see or disobeyed the signal Sg .

60 This weakening of the current in the track circuit of block F also causes the weakening of the solenoid s so that the contact a_9 engages contact a_{11} leaving part of resistance R in the track circuit of block E, thus causing 65 the signal Sf at entrance to block F to

take the caution position, and to cause the permanent magnet P at the right end of block E to be more strongly opposed by coils c, c giving an impulse of less strength upon a following car or train giving a different 70 variable control thereon. And the same strength of current in track circuit of block E allows solenoid s to attract its core c_{14} to its uppermost position to cut out all of the resistance R from the track circuit of block D thus producing a still stronger current in the track circuit of block D which will cause magnet P at the end of block D to be still more strongly opposed and to cause the signal Se at the entrance to block E to go to the 80 safety position. And this will insure a similar condition in all the blocks to the rear which are unoccupied.

It will thus be seen that as a car or train advances it produces a change in the track 85 circuit in the rear to give various signals and it will also change the opposition to the permanent magnets at the ends of the blocks to the rear so as to give varying indications or controls upon following trains. 90 As the car or train moves off the right end of block G the signal Sg will take the caution position and the contact a_9 will engage contact a_{11} at the entrance to block G with the result that signal Sf will go to the safety 95 position and all the resistance R at the entrance to block F will be cut out of circuit producing no change in the signals to the rear.

Besides the permanent magnets P indicated in Fig. 6, any other permanent magnet, as P' may be bridged across the rails of a block, as at the approach to a curve or at any other point where an additional indication or control is to be effected upon 100 the car, the amount of flux produced by such magnet may be made anything desired to produce the desired indication or control upon the train. Or where the train circuit includes a source of energy, the member P' 105 need not be a permanent magnet but may be simply soft iron or steel.

In Fig. 7 the parts are similar to those described in connection with Fig. 6 except however that in place of permanent magnets 110 soft iron or soft steel bars M may be employed and surrounded by an energizing winding w_{10} connected in place of the coils c, c in Fig. 6.

Inasmuch as a flux through the wheel 120 or axle coil C_1 upon a car or train increases with the increase of current strength in the coils w_{10} , (this being opposite to the case of increase of current in coils c, c of Fig. 6) the resistance R and its contacts are so arranged that greater amounts of resistance are brought into the track circuits as the solenoid core c_{14} rises, that is, as the solenoids s are more strongly energized. And in such case the relay or other device of 125

which the w_9 is a part is so arranged that with the strongest current therethrough the associated signal takes the danger position and the caution and clear positions are taken with currents of progressively smaller values.

Here again at the approach to a curve or at any other suitable point a member P' which may be permanently magnetized or may 10 be of soft iron or steel may be placed across the track rails to give an independent indication or control upon the car or train, the same being simply, as in the case of Fig. 6, to cause a change in flux in the coil in the 15 car circuit as the train passes.

In Fig. 8 there are again shown a plurality of blocks or sections D, E, F and G. In the example illustrated the upper or one rail T is conductively continuous while the other, 20 the lower rail T, is divided into lengths corresponding with the blocks or sections by the insulators I. Between the two rails T, T of each block and at one end of each block is connected the track circuit battery 25 or other suitable source of current B_9 , and if desired an adjustable resistance R_8 may be included therewith. And across the track rails T, T of each section or block, but at the opposite end from the battery B_9 , is connected the winding of any suitable relay R_4 , such as a well known track relay or any 30 other equivalent device, which may also control trackway signals, as in Figs. 6 and 7, having the tongue or armature a_{13} pivoted 35 at a_{14} and electrically connected with one terminal of the battery or other suitable source of current B_{10} whose other terminal connects with the upper continuous rail T, it being noted that the terminals or poles of 40 like signs or polarities of B_9 and B_{10} are connected with the continuous rail T. Each armature a_{13} is adapted to engage either of the contacts a_{15} or a_{16} . The conductor c_{16} may be directly connected with the continuous 45 rail so as to adapt system shown in Fig. 8 for use on double rail roads. The coils w_{14} are associated with the several permanent magnets P_1 , P_2 and P_3 of each section or block, it being understood that a greater 50 or less number of such permanent magnets may be employed per section or block if desired. These permanent magnets extend across the rails as hereinbefore described and are insulated from the rail at one end 55 at least by the insulation I. The coils w_{14} all have substantially equal number of convolutions or turns, and they act, when current passes through them, to oppose the magneto-motive forces of their associated 60 permanent magnets so that the magnetic flux through the wheel or axle coils carried by the train or car shall be *nil*, or at least of such small value as to have no effect upon the translating device t upon the car 65 or train. And there may be a connection

from each relay contact a_{16} through the coils w_{15} , disposed upon the same permanent magnets, to the continuous rail or conductor T through the aforementioned conductor c_{16} . It will be noted that the number of turns 70 or convolutions in the coils w_{15} on the different permanent magnets varies, the number of turns in these coils decreasing from left to right, that is, preferably in the direction of the traffic. When current passes through 75 these coils w_{15} they also oppose the magneto-motive forces of their associated permanent magnets, but they do this to varying or different degrees because of their different numbers of turns or convolutions. 80 And it is preferred that the number of turns in the coil w_{15} upon the permanent magnet P_3 , this coil having the maximum number of turns of all the coils w_{15} , shall be 85 less than the number of turns in each of the coils w_{14} , so that in any case the magneto-motive force of the permanent magnet P_3 shall not be completely diverted or neutralized, to the end that the permanent magnet P_3 will nevertheless, when its coil w_{15} is 90 energized, cause sufficient flux through the wheel or axle coils on the car or train to produce an indication or control by the translating device t .

The parts thus far described are suitable 95 for effecting an automatic variable or tapering control or indication for traffic which is always in one and the same direction, in the case illustrated, from left toward the right.

When there is no train or car present in 100 a section or block, the relays R_4 at the rear ends (left ends as illustrated) of the sections or blocks will be energized from their associated track batteries B_9 at the other 105 ends of the blocks, and accordingly their tongues or armatures will be attracted and held in engagement with their contacts a_{15} , as indicated in the drawing at the relays R_4 at the rear ends of block E and F. The result is that the windings w_{14} of the blocks 110 to the rear, that is, of blocks E and D will be energized while the windings w_{15} of these same blocks will be deenergized because the armatures a_{13} are separated from contacts a_{16} . These windings w_{14} receive their current from the associated batteries B_{10} , the current passing from one terminal of such a battery B_{10} to the armature a_{13} , thence through the contact a_{15} , thence through the windings w_{14} and thence through the conductor c_{16} , if it is not connected to the rail, thence to the continuous rail or conductor T and back to the other terminal of the battery. This energization of these coils w_{14} causes such opposition to the magneto-motive forces of the associated permanent magnets P_1 , P_2 and P_3 that should a train or vehicle run into the block occupied by these permanent magnets, the flux that any one of them could produce through the wheel 125 130

- or axle coils upon the vehicle would be *nil* or so small that the translating device *t* thereon would not respond, with the result that there would be no control effected or indication produced on the car or train. In other words those blocks whose coils w_{14} are energized are in the "clear" condition allowing vehicle or train movements thereover at maximum speed.
- 10 But should there be a train or car in a block, as is indicated in block G, the two rails T, T of that block are conductively bridged by the wheels and axles of the car or train, forming a low resistance path for 15 the current from the battery B_9 of the block G. The result is that the relay R_4 at the left end of the block G is deenergized with the result that its armature a_{13} drops away from contact a_{15} and engages contact a_{16} .
- 20 The result is that the coils w_{14} of block F are deenergized but the coils w_{15} of block F are energized, current flowing from the battery B_{10} through the relay tongue a_{13} of relay R_4 at the left end of block G, thence 25 through its contact a_{16} , through the coils w_{15} of block F and through the conductor c_{16} , if it is not connected to the continuous rail, thence to the continuous conductor or rail T which is connected to the other terminal 30 of that battery B_{10} . The result is that the magneto-motive force of the permanent magnet P_3 nearest the left end of the block F is opposed by the ampere turns of its coil w_{15} . But this opposition is not complete 35 for the permanent magnet P_3 is still able to produce such a flux through the wheel or axle coils of a car or train which may enter block F from block E as to produce an effect upon the translating device *t* upon the 40 car or train. But this flux being relatively small will only produce a certain degree of response of the translating device *t*, which may be of the character illustrated in Fig. 4 or of any other suitable type. The result is 45 that if the speed of the train or car so entering from block E to block F is higher than the previously determined or desired speed, the speed will be slackened by the control, or the engineman or motorman will 50 receive such indication that he will reduce the speed of the train or car. If the first mentioned car or train remains in the block G, when the train or car which has entered the block F reaches the permanent magnet 55 P_2 , if the speed of the car or train has not been sufficiently slackened the translating device *t* thereon will make a greater degree of response, because the flux produced by the permanent magnet P_2 in opposition to 60 its coil w_{15} will be greater than that produced by the permanent magnet P_3 . Or if the speed of the car or train has been sufficiently slackened by the time it reaches the permanent magnet P_2 , the response of 65 the translating device *t* may be no different

from that when passing permanent magnet P_3 , because there is less speed though greater flux. And so when reaching the permanent magnet P_1 if the speed has not been still further slackened there will be a still greater 70 response by the translating device *t* which will either automatically bring the speed of the car or train down to a safe speed, or to rest if desired, because the flux produced by the permanent magnet P_1 is even greater 75 than that produced by the permanent magnet P_2 , or will give an indication ordering reduction of speed or complete stop. Or if the speed is below a predetermined value on reaching magnet P_1 , the device *t* may not 80 respond sufficiently to further reduce the speed or bring the car or train to rest.

If while the train or car is moving in the block F the train or car in the block G should move off of the block G into the next 85 block ahead, as block H, not shown, the relay R_4 at the left end of block G will again be energized and will attract its armature a_{13} away from contact a_{16} into engagement with contact a_{15} , with the result that the 90 coils w_{15} of block F will be deenergized and coils w_{14} of block F will be energized, thus in effect clearing the block or allowing maximum speed therein.

Accordingly by the arrangement described 95 as a train or car approaches a section or block that is occupied there is effected upon such train or car an automatic tapering or varying control or indication, the successive controls or indications, as the car or 100 train approaches the occupied block, vary from each other and increase so as to progressively reduce the speed of the car or train.

If, however, traffic is to be allowed in both 105 directions over the track illustrated, the connection of c_{16} to the continuous rail above referred to is not made. In such case the windings w_{14} and w_{15} connect at the left end of each block through a conductor c_{16} with a contact a_{17} carried by but insulated from the tongue or armature a_{13} of the relay R_4 at the rear end of the second preceding block. And this contact a_{17} is adapted to engage with a stationary contact a_{18} connected to the continuous conductor or rail T. 115

Suppose there should be in block E a train or car moving from left toward the right and at the same time there should be in block G moving toward the left a car or train as indicated. In such case the train or car in block E will short circuit the winding of the relay R_4 at the left end of the block E, thereby breaking connection between contact a_{17} and a_{18} of that relay, thus interrupting the circuit through the conductor c_{16} through which connection from both coils w_{14} and w_{15} of block G is made with the continuous conductor or rail T. The result is that neither the coils w_{14} nor 130

the coils w_{15} of block G can be energized, and they are in fact deenergized under this circumstance, with the result that all the permanent magnets in the block G produce 5 maximum flux through the wheel or axle coils of the train or car in block G, thus giving maximum control or indication by its translating device t , bringing such train or car to rest, or suitably reducing its speed. 10 And from the fact that there is a car or train in block G as assumed, the relay R_4 at the left end of block G will be deenergized with the result that the coils w_{15} of block F are energized so that if the train assumed in 15 block E should run into block F it will be suitably controlled or brought to rest as described in connection with traffic in one direction only. Accordingly the last described arrangement of Fig. 8 is suitable for automatically controlling traffic in both directions on a single track railway, the connections by conductors c_{10} from the coils w_{14} and w_{15} of a block to the second block in the rear and there controlled by the track relay, 20 serving in effect to give overlapping controls or indications.

In place of the upper continuous rail T there may be used for the connections of the coils w_{14} and w_{15} and the batteries B_{10} a separate and independent conductor or wire extending along the path of travel.

In the circuit of each group of coils w_{14} may be inserted a resistance R_s for suitably adjusting the current through the coils w_{14} 35 to adjust the degree or extent of their opposition to the magneto-motive forces of their associated permanent magnets. And similarly in the circuit of each group of windings w_{15} may be included a resistance R_s for suitably 40 adjusting the current in these coils to adjust the degree or extent of their opposition to their associated permanent magnets.

While I have described the employment of permanent magnets in Fig. 8, it is to be understood that members of soft iron or steel 45 may be employed in their stead, with associated coils or windings for controlling the flux through them and through the wheel or axle coils on the car or train, such soft iron or steel members cooperating in any of the ways hereinbefore described.

It will be understood as to Figs. 6, 7 and 50 8 that conductors other than the track rails may be employed in the circuits including those track rails.

The selectively or variably responsive translating device t on the car or train may effect or cause any desired signals or indications, or may control the speed of the car or train by controlling the air or other brakes to varying degrees or by controlling the speed of the driving engine or motor.

In Fig. 9 there is no car circuit, the translating device t_1 to effect any suitable variable controls, indications or signals at predet-

mined points along the trackway being included in a circuit with the coils, w , w and the source of energy or battery B_2 and adjustable resistance R_2 as in Fig. 2. The coils w , w are disposed upon the soft iron or steel 70 cores c , c constituting poles for the permanent magnet P extending across the trackway.

In this case the iron or steel wheels and axle moving over the permanent magnet P 75 reduce and then increase the reluctance of its magnetic circuit, thus inducing current in the coils c , c producing an effect, as hereinbefore described, upon the translating device t_1 .

It will be understood that where a permanent magnet is used as described, the source B_2 may be omitted for in such case also current will be induced in the coils c , c upon the passage of wheels and axle.

And when the source B_2 is present, the permanent magnet P may be replaced by a bar or bars of soft iron or steel and current will nevertheless be induced in the coils c , c .

The translating device t_1 may be used to 90 count cars passing the coils c , c or may be used for effecting any control or indication or signal. There will be a response for each pair of wheels and axle passing.

While in the arrangements hereinbefore 95 described the permanent magnets or masses of soft iron or steel have been referred to as substantially straight bars or laminated bars extending across the track, such permanent magnets or soft iron or soft steel members may be U-shaped or in the shape of a horse shoe magnet as indicated in Fig. 10 at P₄. Such shape is of particular advantage when the member P₄ is a permanent magnet for in such case the magnetic circuit through the permanent magnet itself is longer, and the portion of the magnetic circuit through the rails, wheels and axle are relatively a smaller part of the entire length of magnetic circuit. It will be understood that such U-shaped or horse shoe permanent magnet or other material may be used in any of the arrangements hereinbefore described, any of the coils or exciting coils and their circuits hereinbefore described being understood to 100 be applicable as well to this form of permanent magnet or mass of soft iron or soft steel. And it will be understood that such member P₄ may be buried in the track ballast or disposed in any suitable way; and 105 that the same may be laminated.

And while I have hereinbefore described the permanent magnets or masses of soft iron or steel as extending across the tracks, it will be understood that one or both of 110 the track rails T may have interpolated in them a section of rail T_m of non-magnetic or substantially non-magnetic material such as manganese steel, as shown in Fig. 11. In this case the permanent magnet or mass of 115

soft iron or steel, whether in the form of a bar or in U-shape or in the form of a horse shoe may have its ends or poles applied to the adjacent ends of the rails T, T, the section T_m being disposed between the ends or poles. Preferably the poles or ends of the members P₄ are substantially as far apart as the two wheel axles A, A of a truck and the rail T_m is preferably shorter than the distance between the poles of P₄. The two wheels W, W, on one side of the truck and running upon the same rail, have some connection between them of magnetic material, such as the beam or member M₁, which may be a part of the usual truck frame or structure. It will be understood that as the truck passes over the rails the flux through the wheel coils, or a coil surrounding the member M₁, will be varied producing effects in the circuit of the coil or coils as upon the translating device t of any suitable character such as herein described. And the other wheels of the same truck running on the other rail, not shown, may be similarly equipped, and the other rail may be similarly equipped with a member T_m and a member P₄, in which case the coil or coils coöperating with such other member P₄, may coöperate with the first named coil or coils in controlling or affecting the car or train circuit, and such other member P₄ may have applied thereto windings or exciting coils in accordance with any of the arrangements hereinbefore described.

35 While I have herein shown wheel coils in some instances and axle coils in others it is to be understood that my invention is not so limited, for I may use wheel coils where axle coils are illustrated, and I may use axle coils where wheel coils are illustrated, or I may use both wheel and axle coils in any case. And where a plurality of coils is used they may be connected in series, or in parallel with each other.

40 45 What I claim is:

1. The combination with a traveling vehicle, of a member of magnetic material disposed in the path of travel of said vehicle, an electric circuit on said vehicle in coöperative relation with said member, a translating device in said circuit responsive in different degrees to different magnitudes of current in said circuit, and means controlled to different degrees by said translating device as the latter responds in different degrees.
2. The combination with a traveling vehicle, of a magnet disposed in its path of travel, an electric circuit on said vehicle in coöperative relation with said magnet, a translating device responsive in different degrees to currents of different strengths resulting in said circuit from coöperation of said circuit with said magnet, and vehicle speed controlling means controlled to dif-

ferent degrees by said translating device as the latter responds in different degrees.

3. The combination with a traveling vehicle, of a magnet disposed in its path of travel, an electric circuit on said vehicle in coöperative relation with said magnet, a translating device responsive in different degrees to currents of different strengths resulting in said circuit from coöperation of said circuit with said magnet, vehicle speed controlling means controlled to different degrees by said translating device as the latter responds in different degrees, and traffic controlled means controlling said magnet.

4. The combination with a traveling vehicle, of a permanent magnet disposed in the path of travel of said vehicle, an electric circuit on said vehicle inductively influenced by said magnet, a translating device in said circuit responsive in different degrees to different magnitudes of current in said circuit, means controlled to different degrees by said translating device as it responds in different degrees, a circuit including a source of current and a winding associated with said magnet, and means controlling the strength of current in said last named circuit for varying the inductive effect of said magnet upon said vehicle circuit.

5. The combination with a traveling vehicle, of a permanent magnet disposed in the path of travel of said vehicle, an electric circuit on said vehicle inductively influenced by said magnet, a translating device in said circuit responsive in different degrees to different magnitudes of current in said circuit, means controlled to different degrees by said translating device as it responds in different degrees, a circuit including a source of current and a winding associated with said magnet, and means automatically responsive to traffic conditions controlling the strength of current in said last named circuit for varying the inductive effect of said magnet upon said vehicle circuit.

6. The combination with a traveling vehicle, of a magnet disposed in the path of travel thereof, a vehicle circuit inductively influenced by said magnet, a translating device responsive in different degrees to electro-motive-forces of different magnitudes induced in said circuit, and means controlling said magnet to produce different quantities of flux greater than zero in response to different traffic conditions in the path of travel of said vehicle.

7. The combination with a traveling vehicle, of a permanent magnet disposed in the path of travel thereof, a vehicle circuit inductively influenced by said permanent magnet, a translating device responsive in different degrees to electro-motive-forces of different magnitudes induced in said circuit,

and means controlling said permanent magnet to produce different quantities of flux greater than zero in response to different traffic conditions in the path of travel of said vehicle.

8. The combination with a traveling vehicle, of a permanent magnet disposed in the path of travel thereof, a vehicle circuit inductively influenced by said permanent magnet, a translating device responsive in different degrees to electro-motive-forces of different magnitudes induced in said circuit, means controlling said permanent magnet to produce different quantities of flux greater than zero in response to different traffic conditions in the path of travel of said vehicle, and a brake valve controlled by said translating device.

9. The combination with a traveling vehicle, of a magnetizable member disposed in the path of travel of said vehicle, a winding associated with said magnetizable member, a translating device and a source of current included in circuit with said winding, and means moving with said vehicle for causing changes in magnetic flux in said winding, said translating device responding to said changes in flux in the track magnet winding.

10. The combination with a traveling vehicle, of a magnetizable member disposed in the path of travel of said vehicle, a winding associated with said magnetizable member, a variably responsive translating device and a source of current included in circuit with said winding, and means moving with said vehicle for causing changes in magnetic flux in said winding.

11. The combination with a traveling vehicle, of a permanent magnet disposed in the path of travel of said vehicle, a winding associated with said permanent magnet, a variably responsive translating device included in circuit with said winding, a magnetizable mass movable with said vehicle, and means on said vehicle for producing in said mass a magnetic flux.

12. The combination with the rails of a railway, of a horse shoe permanent magnet having its ends or poles juxtaposed to said rails, a vehicle traveling upon said rails, a circuit including a translating device, and a magnetizable mass movable with said vehicle for changing the magnetic flux inclosed by said circuit.

13. The combination with a path of travel, of a vehicle movable thereover, a circuit and a member of magnetic material, one of which is disposed on said vehicle and the other in said path of travel, and a translating device responsive to different degrees controlled by said circuit, and traffic controlling means controlled to different degrees by said translating device as it responds in different degrees.

14. The combination with a moving ve-

hicle, of an electric circuit thereon including a variably responsive translating device, an air brake system on said vehicle, a valve controlling said system, means variably controlled by said translating device for causing said valve to take different positions, a permanent magnet or a magnetizable mass disposed in the path of travel of said vehicle, said translating device affected to varying degrees in response to varying effects of vehicle speed and magnetic flux, whereby said valve automatically takes said different positions.

15. The combination with a moving vehicle, of an electric circuit thereon including a variably responsive translating device and a source of current, an air brake system on said vehicle, a valve controlling said system, means variably controlled by said translating device for causing said valve to take different positions, a permanent magnet or a magnetizable mass disposed in the path of travel of said vehicle, said translating device affected to varying degrees in response to varying effects of vehicle speed and magnetic flux, whereby said valve automatically takes said different positions.

16. The combination with a traveling vehicle, of a circuit wholly disposed thereon including a variably responsive translating device, and means disposed along the path of travel of said vehicle for progressively changing the magnetic fluxes inclosed by said circuit.

17. The combination with a traveling vehicle, of a circuit thereon including a translating device, and means disposed along the path of travel of said vehicle for progressively changing the magnetic fluxes inclosed by said circuit, said means comprising a plurality of permanent magnets.

18. The combination with a traveling vehicle, of a circuit thereon including a variably responsive translating device, and means disposed along the path of travel of said vehicle for progressively changing the magnetic fluxes inclosed by said circuit, said means comprising a plurality of permanent magnets.

19. The combination with a traveling vehicle, of a circuit thereon including a translating device, means disposed along the path of travel of said vehicle for progressively changing the magnetic fluxes inclosed by said circuit, and means responsive to the presence of a vehicle on said path of travel at a distance from said first named vehicle for increasing one or more of said fluxes.

20. The combination with a traveling vehicle, of a circuit thereon including a variably responsive translating device, means disposed along the path of travel of said vehicle for progressively changing the magnetic fluxes inclosed by said circuit, and means responsive to the presence of a ve-

hicle on said path of travel at a distance from said first named vehicle for increasing one or more of said fluxes.

21. The combination with a traveling vehicle, of a circuit thereon including a translating device, means disposed along the path of travel of said vehicle for progressively changing the magnetic fluxes inclosed by said circuit, and means responsive to the presence of a vehicle on said path of travel at a distance from said first named vehicle for rendering all said fluxes substantially equal and greater than the least of said fluxes.

15 22. The combination with a traveling vehicle, of a circuit thereon including a translating device, means disposed along the path of travel of said vehicle for progressively changing the magnetic fluxes inclosed by 20 said circuit, and means responsive to the presence of a vehicle on said path of travel at a distance from said first named vehicle for rendering all said fluxes substantially equal to the greatest of said fluxes.

25 23. The combination with a traveling vehicle, of a circuit thereon including a translating device, means disposed along the path of travel of said vehicle for progressively changing the magnetic fluxes inclosed by 30 said circuit, and means responsive to the presence of a vehicle on said path of travel at a distance from said first named vehicle for reducing said fluxes to such degree that said translating device is non-responsive.

35 24. The combination with a plurality of blocks, of a traveling vehicle, a circuit including a translating device disposed upon said vehicle, a plurality of sources of magneto-motive force disposed along the path of 40 travel of said vehicle within a block, windings adapted to produce magneto-motive forces in opposition to the magneto-motive forces produced by said sources, and means responsive to the condition of another block 45 controlling said windings.

25. The combination with a plurality of blocks, of a traveling vehicle, a circuit including a translating device disposed upon said vehicle, a plurality of sources of magneto-motive force disposed along the path of 50 travel of said vehicle within a block, windings adapted to produce magneto-motive forces in opposition to the magneto-motive forces produced by said sources, and means 55 responsive to the condition of another block controlling said windings, said windings producing magneto-motive forces of different intensities.

60 26. The combination with a plurality of blocks, of a traveling vehicle, a circuit on said vehicle including a translating device, a plurality of permanent magnets disposed along the path of travel of said vehicle within a block, windings associated with said 65 permanent magnets producing different

numbers of ampere turns, and means responsive to the condition of another block for controlling said windings.

27. The combination with a plurality of blocks, of a traveling vehicle, a circuit on 70 said vehicle including a translating device, a plurality of permanent magnets disposed along the path of travel of said car within a block, windings associated with said magnets adapted to reduce the magnetic fluxes 75 successively inclosed by said vehicle circuit to a degree to render said translating device unresponsive, and means responsive to the condition of another block controlling said windings.

28. The combination with a plurality of blocks, of a traveling vehicle, a circuit on said vehicle including a translating device, a plurality of permanent magnets disposed along the path of travel of said vehicle within a block, windings associated with said magnets adapted to reduce the magnetic fluxes successively inclosed by said vehicle circuit to a degree to render said translating device unresponsive, additional windings associated with said permanent magnets producing different numbers of ampere turns in opposition to the magneto-motive forces of said permanent magnets, and means responsive to the condition of another block 95 for causing energization of one or the other of said sets of windings.

29. The combination with a plurality of blocks, of a traveling vehicle, a circuit on 100 said vehicle including a translating device, a plurality of permanent magnets disposed along the path of travel of said vehicle within a block, windings associated with said magnets adapted to reduce the magnetic fluxes successively inclosed by said vehicle circuit to a degree to render said translating device unresponsive, additional windings associated with said permanent magnets producing different numbers of 105 ampere turns in opposition to the magneto-motive forces of said permanent magnets, and means responsive to the condition of another block preventing or permitting the energization of either set of windings.

30. The combination with a plurality of 110 blocks, of a traveling vehicle, a circuit on said vehicle including a translating device, a plurality of permanent magnets disposed along the path of travel of said vehicle within a block, windings associated with 115 said magnets adapted to reduce the magnetic fluxes successively inclosed by said vehicle circuit to a degree to render said translating device unresponsive, additional windings associated with said permanent magnets producing different numbers of 120 ampere turns in opposition to the magneto-motive forces of said permanent magnets, means responsive to the condition of another block for causing energization of 130

one or the other of said sets of windings, and means responsive to the condition of a third block for permitting or preventing control of either set of said windings by 5 said last named means.

31. The combination with a traveling vehicle, of a circuit thereon including a variably responsive translating device, variable speed controlling means controlled by 10 said translating device, means disposed along the path of travel of said vehicle for affecting the amount of magnetic flux enclosed by said vehicle circuit, and means responsive to traffic conditions on said path 15 of travel for controlling said means, whereby the speed of said car at any point on said path of travel is automatically determined.

32. The combination with a traveling vehicle, of a circuit thereon including a variably responsive translating device, variable speed controlling means controlled by said translating device, a plurality of magnetic flux determining members disposed along 25 the path of travel of said vehicle, means responsive to traffic conditions on said path of travel controlling said members, the fluxes controlled by said members increasing progressively in the direction of travel 30 of said vehicle, whereby less than predetermined speed of said vehicle is insured at predetermined points in its path of travel.

33. The combination with a traveling vehicle, of an electric circuit thereon including a variably responsive translating device, variable speed controlling means controlled by said translating device, a plurality of magnetic flux controlling members disposed along the path of travel of said 40 vehicle, and means responsive to traffic conditions on said path of travel either in advance of or in the rear of said vehicle controlling said members, whereby the speed of said vehicle is caused to diminish to or not 45 exceed a predetermined speed at a predetermined distance from said means.

34. The combination with a traveling vehicle, of an electric circuit thereon including a variably responsive translating device, variable speed controlling means controlled by said translating device, a plurality of magnetic flux controlling members disposed along the path of travel of said vehicle, and means responsive to traffic conditions on said path of travel either in advance of or in the rear of said vehicle controlling said members, whereby the speed of said vehicle is caused to diminish to or not 55 exceed a predetermined speed at a predetermined distance from said means, the flux caused or controlled by said members increasing in the direction of travel of said vehicle.

35. The combination with a moving vehicle, of an electric circuit thereon including

vehicle controlling means selectively responsive to different electro-motive forces impressed upon said circuit, a series of magnetic members spaced along the path of travel of said vehicle, and means responsive 70 to the presence of and movement of another vehicle on said path of travel for causing progression along said path of travel of a variation in the magnetic fluxes of said members, whereby said second vehicle maintains 57 a predetermined space between itself and said first named vehicle.

36. The combination with a moving vehicle, of an electric circuit on said vehicle including a vehicle controlling translating 80 device, a series of magnetic members spaced along the path of travel of said vehicle, and means responsive to the presence of and movement of another vehicle or obstacle on said path of travel for causing progression 85 along said path of travel of a variation in the magnetic fluxes of said members, whereby said second vehicle or obstacle maintains a predetermined space between itself and said first named vehicle. 90

37. The combination with a traveling vehicle, of an electric circuit thereon including a translating device, of a series of magnetic members spaced along said path of travel, said circuit on said vehicle adapted to inclose magnetic flux of said members, and means responsive to the movement of another similarly equipped vehicle along said path of travel for causing a progression along said path of travel of predetermined 100 variation of said magnetic fluxes, whereby said translating device on said first named vehicle responds upon approach of said first named vehicle within a predetermined distance of said second named vehicle, and means responsive to the position of said first named vehicle causing a translating device of said second vehicle similarly equipped to respond when said vehicles approach each other within a predetermined distance. 110

38. The combination with a moving vehicle, of an electric circuit on said vehicle including a translating device, a series of magnetic members spaced along the path of travel of said vehicle, means responsive to the presence of and movement of another vehicle on said path of travel for causing progression along said path of travel of a variation in the magnetic fluxes of said members, whereby said second vehicle maintains 120 a predetermined space between itself and said first named vehicle, and speed controlling means on said first named vehicle controlled by its translating device.

39. The combination with a traveling vehicle, of an electric circuit thereon including a translating device, of a series of magnetic members spaced along said path of travel, said circuit on said vehicle adapted to inclose magnetic flux of said members, means re- 125 130

sponsive to the movement of another similarly equipped vehicle along said path of travel for causing a progression along said path of travel of predetermined variation 5 of said magnetic fluxes, whereby said translating device on said first named vehicle responds upon approach of said first named vehicle within a predetermined distance of said second named vehicle, and means responsive to the position of said first named vehicle causing a translating device of said second vehicle similarly equipped to respond when said vehicles approach each other within a predetermined distance; and speed 10 controlling means on said vehicles controlled by their translating devices.

40. The combination with a plurality of blocks, of a traveling vehicle, a circuit including a translating device disposed upon

20
25
30

said vehicle, a plurality of sources of magneto-motive force disposed along the path of travel of said vehicle within a block, windings adapted to produce magneto-motive forces in opposition to the magneto-motive forces of said sources, a continuous conductor common to neighboring blocks, a circuit including said continuous conductor and said windings, and means responsive to the condition of another block controlling said circuit.

In testimony whereof I have hereunto affixed my signature in the presence of the two subscribing witnesses.

GEORGE P. FINNIGAN.
